UNITED STATES PATENT OFFICE.

EDWARD Y. MOORE, OF CLEVELAND, OHIO.

HOISTING MECHANISM.

1,130,420.

Specification of Letters Patent. Patented Mar. 2, 1915.

Application filed July 13, 1914. Serial No. 350,582.

To all whom it may concern:

Be it known that I, EDWARD Y. MOORE, a citizen of the United States, residing at Cleveland, in the county of Cuyahoga and State of Ohio, have invented a certain new and useful Improvement in Hoisting Mechanism, of which the following is a full, clear, and exact description, reference being had to the accompanying drawings.

10 In the employment of portable hoists it frequently happens that it is desired to use a hoist repeatedly at definite points, while in the meantime it is desirable to have it out of the way or in use at some other point.

15 The object of this invention is to provide a portable hoist with simple supporting means so arranged that the hoist may be rolled along a trackway to its point of use and there supported for use without the necessity of employing the weight or head

20 room incident to a trolley sufficient to support the load. To this end I provide a trolley device connected with a hoist frame and strong enough to support the weight of the hoist without the load, and I provide means 25 operable at the desired points of use to take the weight off the transporting wheels and suspend the hoist directly from the trackway.

30 My invention accordingly comprises a hoist provided with a transporting structure sufficient to support the weight of the hoist, and an independent supporting device adapted to carry both the weight of the hoist and the weight of the load.

My invention includes also more particularly the mechanism illustrated in the drawings hereof for carrying out such operation.

40 In the drawings, Figure 1 is an end view of a hoist provided with the supporting mechanism of this invention, the trackway being shown in section; Fig. 2 is a side elevation of such hoist and trackway.

45 The hoist proper shown in the drawings is substantially that shown, described and claimed in my prior Patent No. 1,035,030, but it is to be understood that such embodiment is chosen as illustrative, and any suitable hoist may be employed and equipped with my invention.

As shown, 10 represents the hoist frame which is in the form of a casing containing pocket wheels and gearing (not shown) 55 driven by suitable hand wheels 11. The lift chain 12 is shown as depending from the

pocket wheels within the frame around sheaves 14 in the block 15 which carries the eye-bar 16 for receiving the load.

To support the hoist mentioned and allow 60 its easy transportation from its place of storage to its place of use, I provide an overhead trackway which, in effect, is a large hollow I-beam. As shown this trackway is composed of parallel plates 20 having angle 65 irons 21 in their upper ends and angle irons 22 near their lower ends. The plates are shown as separated by distance sleeves 24 through which pass bolts 25. The essential part of the trackway in the embodiment 70 shown, so far as the present invention is concerned, consists of the lower flanges 22 and the space between the side members 20, and the trackway may be of any form so long as it has these characteristics or their equivalent. 75

Secured to the hoist frame and rising therefrom on opposite sides are brackets 30, each of which carries a pair of wheels 31 riding on the flanges 22. This serves to 80 transport the hoist from place to place after the manner of a trolley. The structure, however, is not of sufficient dimensions to support the load. Secured centrally to the hoist frame is a plate 35 which is shown as 85 set into the space usually occupied by the hook and extending on each side thereof and firmly secured by bolts 36. This plate extends upwardly between the side plates 20 of the trackway. Through the plate is an 90 opening 38. Located at the proper point or points in the trackway are openings 28 through the plates 20, which openings are adapted to register with the opening 38. Through the registering openings is driven 95 a wedge 40 which raises the hoist sufficiently to take the weight off the wheels and support it entirely by the plate 35. The plate 35 and wedge are of such dimensions as to support the entire load which the hoist may 100 lift. The openings 28 have their lower ends just above the upper edges of the angle flanges 22 so that an effective support is provided for the wedge.

It will be noticed that my construction 105 brings the hoist frame close to the under side of the trackway, doing away with any waste of head room. The supporting attachments for the hoist are simple and easily secured to the hoist frame and enable it to 110 be effectively transported to and from its point of use.

Having thus described my invention, what I claim is:

1. The combination, with a trackway and a hoist suspended therefrom, of means for supporting the weight of the hoist without supporting the weight of the load whereby the hoist may be transported along the trackway, and independent means for supporting the hoist and load.
- 10 2. The combination of a flanged trackway, a depending hoist provided with wheels adapted to roll on said trackway, and means to support the hoist from the trackway independently of the wheels.
- 15 3. The combination, with a trackway, of a hoist provided with wheels riding on the trackway, a member rising from the hoist, and means for locking said member to the trackway to support the weight of the load.
- 20 4. The combination of a trackway, a hoist provided with wheels adapted to travel on the trackway, a member rising from the hoist, and a wedge adapted to engage said member and the trackway and thereby support the hoist from the trackway independently of the wheels.
- 25 5. The combination of a flanged trackway having a downward opening, a hoist having wheels riding on the flanges and provided with a member extending upwardly into said opening, and means to lock said member to the trackway.
- 30 6. The combination of a flanged trackway having a downward opening, a hoist having wheels riding on the flanges and provided with a member extending upwardly into said opening, and a bar passed crosswise through registering openings in the trackway and said member.
- 35 7. The combination of a trackway having upright plates spaced apart and outstanding flanges, a hoist having wheels riding on said flanges, a member secured to the hoist frame and extending upwardly between the plates, there being an opening through said member and openings through the plates of the trackway, and a wedge adapted to occupy said openings.
- 40 8. The combination, with a hoist frame, of a pair of standards rising therefrom, wheels carried by said standards, an intermediate member secured to the hoist frame and rising between the wheels of the two standards, and a trackway adapted to support said wheels, and means to support said member from the trackway independently of the wheels.
- 45 9. The combination of a trackway having a pair of vertical plates spaced apart and each provided with an outstanding flange adjacent to its lower edge, registering open-
- 50 ings through said plates, a hoist having a frame below said trackway, standards secured to the hoist frame and rising outside of and above the flanges, wheels on the inner sides of the standards riding on said flanges, a plate secured centrally to the hoist frame and rising between the plates of the trackway and provided with an opening adapted to register with the opening of the trackway, and a wedge extending transversely through such registering openings to support the weight independently of said wheels.
- 55 10. The combination, with a supporting trackway, of a depending hoist having wheels adapted to ride on the trackway whereby the hoist may be transported along the trackway, and means for supporting the hoist from the trackway structure independently of the wheels.
- 60 11. The combination of an elevated trackway comprising flanges and supporting means therefor, and a depending hoist having wheels riding on the trackway and provided with means whereby it may be supported directly from the supporting means for the flanges independently of the wheels.
- 65 12. The combination, with an elevated supporting structure having a trackway, of a depending hoist having wheels adapted to ride on the trackway, a support for the hoist additional to the wheels extending upwardly from the hoist, and means for engaging said support to the trackway structure.
- 70 13. The combination, with a trackway structure having upright plates spaced apart and outstanding flanges, of a hoist having wheels riding on said flanges, a member secured to the hoist and extending upwardly between the plates, and means for securing said member to the trackway structure.
- 75 14. The combination, with a trackway structure having a pair of vertical plates spaced apart and each having secured to it near its lower edge an angle bar providing an outstanding flange, registering openings through the plates immediately above the vertical portions of the angle bars, a hoist frame below the trackway, wheels connected with the frame and adapted to ride on the outstanding flanges, a member secured to the hoist frame and rising between the plates, and a cross bar adapted to extend through the registering openings in the plates and engage and support said member.
- 80 15. In testimony whereof, I hereunto affix my signature in the presence of two witnesses.
